CUSHION REST ATTACHMENT FOR
TELEPHONE INSTRUMENTS

John P. Bourdious, New York, N. Y.

Application April 21, 1944, Serial No. 532,177

2 Claims. (Cl. 179—100)

1

This invention relates to a cushion rest attachment for telephone instruments.

When replacing the hand telephone instrument upon its stand, a clattering sound occurs due to contact of the instrument with its supporting stand which, in business offices where many telephones may be in use, as well as in domestic surroundings, becomes annoying to those persons within hearing distance. It is therefore the primary object of this invention to provide an attachment for the stand of the hand telephone instrument which, when in applied position, forms a non-sounding cushion seat for the instrument, which eliminates annoying sounds when the instrument is replaced upon its supporting stand after use.

Another feature of the invention resides in a cushion rest attachment which may be fitted to the supporting stand of the instrument without marring of the same, and without interfering with the telephone company's service to a subscriber.

A further feature of the invention is the provision of a cushion rest attachment containing advertising matter which is prominently displayed when the attachment is in its applied position, thus making the attachment suitable for manufacture and distribution by an advertiser for goodwill purposes.

A still further feature of the invention is the provision of a cushion rest attachment as aforesaid, which is simple of construction, inexpensive of manufacture, and which may be applied in position upon the stand of a telephone instrument by one unskilled in the art.

Other novel features of the invention will become apparent as the following specification is read in conjunction with the accompanying drawing, in which

Figure 1 is a front elevational view of the modern conventional design of telephone instrument showing my cushion rest attachment in position thereon.

Figure 2 is an enlarged detail vertical transverse sectional view on the line 2—2 of Figure 1.

Figure 3 is a perspective view of the cushion rest attachment per se.

Referring to the drawing by reference characters, 10 designates a cushion rest attachment in its entirety for use upon the latest conventional design of telephone set A, which includes a stand B and a combined transmitter and receiver hand instrument C. Normally when the instrument C is at rest, it is supported by spaced saddle rests D—D, through which slidable switch buttons E—E extend and which buttons when depressed

2

by the weight of the instrument C, closes the subscriber's telephone circuit. Intermediate the saddle rests D—D, the stand B is provided with a rearwardly extending flat ledge F, the underside of the edge of which is provided with a downwardly extending bead G. It is in association with the ledge F that the cushion rest attachment 10 is intended for use, for supporting the instrument C when at rest upon the stand B.

The cushion rest attachment 10 comprises a flat elongated base 11 approximating the distance between the saddle rests D—D, and a width to overlie the ledge F and extend forwardly thereof. The base 11 is preferably constructed of a plastic substance which may be molded or bent to form an integral upwardly and rearwardly extending flange 12 along the front edge thereof. The flat front face of the flange 12 may contain advertising display indicia 13, or it may contain the personal name of the individual user of the telephone set. Formed integral with the rear edge of the base 11 and extending downwardly and forwardly thereof is a resilient hook shaped clip 14, the same terminating in a downturned lip 15. The terminal lip 15 is normally in relatively close spaced relation to the underside of the flat base 11 at a point midway the width thereof. Formed integral with the base 11 and rising upwardly therefrom is a dovetail rib 16, the same extending parallel to and adjacent the flange 12.

Carried by the flat base 11 is a cushion body 17 made of a non-sounding material, preferably moldable sponge rubber, although other materials having like characteristics may be used if desired. The cushion body 17 overlies the entire surface of the base and its front edge is bevelled as at 18 to conform to and fit against the rear face of the flange 12. The underside of the cushion body 17 is provided with a dovetail recess 19 which receives the dovetail rib 16. The interlocking engagement of the rib 17 and walls of the recess 19 acts to securely hold the cushion body in position upon the base, and these parts are brought into interlocking relation during assembly by spreading the side walls of the recess 19 by longitudinal flexing of the cushion body, so as to clear the longitudinal edges of the rib 16. If desired, the cushion body may be attached to the base by cement or other adhesive.

To attach the cushion rest 10 in position of use upon the telephone stand B, the hand instrument C is lifted from its saddle rests D—D. The operator may now insert the cushion rest attachment 10 over the ledge F and slide the same

forwardly to cause the hook clip 14 to yield and clampingly engage the underside of the ledge as best illustrated in Figure 2. The down-turned lip 15 acts to guide the clip over the bead edge G during insertion of the cushion rest to its final position of rest. The combined thickness of the base 11 and cushion body 17 is such as not to prevent the handle of the hand instrument from depressing the switch pins E—E to circuit closing position when the instrument is replaced upon the cushion body 17 of the attachment 10. With the attachment 10 in position upon the stand B of the telephone set A, it will be understood that by reason of the cushion body 17 being constructed of a non-sounding material, there will be no clattering or clicking noises, which otherwise occurs when the hand instrument is replaced upon its support, such noises being caused by contact of the hard resonant materials of which the stand and hand instrument are constructed.

When the attachment 10 is in position of use upon the stand B, the display indicia 13 will be prominently displayed for view by a user of the telephone set A.

While I have shown and described what I consider to be the preferred embodiment of my invention, I wish it to be understood that such changes in construction, design, and materials

as come within the scope of the appended claims may be resorted to if desired without departing from the spirit of my invention.

Having thus described my invention, what I claim as new and desire to secure by Letters Patent of the United States is:

1. In combination, a hand telephone instrument and a stand therefor, said stand having a horizontal ledge, a cushion rest attachment comprising a flat rigid base resting upon the ledge, clamping means connected to said base and engaging the underside of said ledge, and a resilient cushion fixedly mounted on the upper side of the base for receiving the hand telephone instrument at rest upon said stand, said base having its front edge turned upward along the adjacent edge of said resilient cushion.

2. In combination, a hand telephone instrument and a stand therefor, said stand having a horizontal ledge, a cushion rest attachment comprising a flat rigid base resting upon the ledge, clamping means connected to said base and engaging the underside of said ledge, and a resilient cushion fixedly mounted on the upper side of the base for receiving the hand telephone instrument at rest upon said stand.

JOHN P. BOURDIUS.
